CLAIM

The ornamental design for a next oil change indicator manual rotatable odometer, as shown and described.

DESCRIPTION

FIG. 1 Illustrates a top front isometric view of a next oil change indicator manual rotatable odometer showing our new design;

FIG. 2 illustrates a bottom isometric view thereof;

FIG. 3 illustrates a front view thereof;

FIG. 4 illustrates a rear view thereof;

FIG. 5 illustrates a right side view thereof;

FIG. 6 illustrates a left side view thereof;

FIG. 7 illustrates a bottom view thereof; and,

FIG. 8 illustrates a top view thereof.
